UNITED STATES PATENT OFFICE.

ALBERT L. LAMBERT, OF NARBERTH, PENNSYLVANIA, ASSIGNOR TO HEINTZ MANUFACTURING COMPANY, OF PHILADELPHIA, PENNSYLVANIA, A CORPORATION OF PENNSYLVANIA.

RUNNING BOARD FOR VEHICLE BODIES.

Application filed October 21, 1924. Serial No. 744,873.

To all whom it may concern:

Be it known that I, ALBERT L. LAMBERT, a citizen of the United States, residing at Narberth, in the county of Montgomery and 5 State of Pennsylvania, have invented certain new and useful Improvements in Running Boards for Vehicle Bodies, of which the following is a specification.

This invention relates to running boards 10 for vehicle bodies, and more particularly relates to running board construction for automobile bodies.

The principal object of my invention is to 15 provide a vehicle running board of sheet metal, to obtain a light and inexpensive construction, and at the same time to provide a running board which is rigid, sturdy, and durable, and one which will withstand the strains and stresses of use.

Another object of my invention is to provide a sheet metal running board, stiffened and reenforced by a single rib, so located 20 and designed that the rib will take the total stress due to a person stepping on the board at the middle, and also will prevent local depression of the running board when the stress is applied on either side of the rib, and whereby is obtained the reenforcement 25 effect of two straight ribs, yet requiring only the amount of metal necessary for one rib.

Other objects of my invention will be in part obvious and in part pointed out hereinafter.

In accordance with my invention, I reinforce a sheet metal running board by 35 means of a tortuous rib running longitudinally along the underside of the board. This rib may either be formed by folding a portion of the metal sheet upon itself, so as to stand at right angles to the plane of the board, or a separate tortuous rib member may be attached to the underside of the board, by welding or riveting or the like. The edges of the board are preferably reinforced and strengthened by flanges, which 40 extend downward at an angle to the plane of the board. Also, if desired, a recess may be formed along the top of the board to receive a linoleum pad, which is usually applied. In this modification, the formed recess acts as a stiffener for the edge of the 45 board.

In order that a clearer understanding of my invention may be had, attention is here-

by directed to the accompanying drawings, 55 forming a part of this application and illustrating certain possible embodiments of my invention.

Referring to the drawings:

Fig. 1 is a top view of a running board 60 embodying my invention;

Fig. 2 is a vertical sectional view thereof, and is taken on the line 2—2 of Fig. 1;

Fig. 3 is an enlarged vertical sectional 65 view of a portion of a running board embodying my invention, showing a means of applying a linoleum pad thereto;

Fig. 4 is a vertical sectional view of a modified form of running board embodying my invention, and including a recess for 70 a linoleum pad;

Fig. 5 is an enlarged vertical sectional view of a portion of the running board shown in Fig. 4, showing one means of holding a linoleum pad in place on the board; 75 and

Fig. 6 is a vertical sectional view of a running board, showing another possible modification of the construction.

Similar reference characters refer to similar parts throughout the several views of the drawings.

Referring to the drawings, the running board in all the modifications shown in the drawings is constructed of an integral piece 85 of sheet metal provided with a tortuous rib running longitudinally along the underside of the board. In the modification shown in Figs. 1, 2 and 3, this tortuous rib 1 is formed by folding a portion of the metal sheet 2 on itself in such a way that the rib stands at right angles to the plane of the board. In this modification, the top of the board is straight and flat. The outer edge of the board is flanged downwardly, as at 3, and then doubled back, as at 4, forming a stiffening and reenforcing flange along this edge. The rear edge of the board may be flanged downwardly, as at 5, and is adapted to be supported from the side splash 6 of the vehicle body, as by resting on a horizontal flange 7 formed along the lower edge of the side splash 6. The ends of the running board may be flanged downwardly, as at 8, with either a single flange or a 100 double flange.

If it is desired to secure a pad 9 of linoleum or other material on the top of this

running board, this may be accomplished, as shown in Fig. 3, by means of securing one or more retaining strips 10 along the outer and side edges of the board, these retaining strips preferably having vertical flanges 11, which may be bolted, as at 12, to the flanges of the running board, and hold the linoleum pad 9 in place by means of horizontal upper flanges 13, which over-
10 lap the front and side edges of the pad 9.

Referring to Figs. 4 and 5, the running board, if desired, may be formed of an integral piece of sheet metal 14, with a tortuous rib 15 running longitudinally along the
15 underside of the board and formed by folding a portion of the sheet metal upon itself, as in the previous modification. As shown, the board may have a recess 16 formed in its top to receive the usual linoleum pad 17.
20 This pad may be retained in place by means of angle-shaped retaining members 18, which may be secured to the outer edge flange 19 of the running board and also to the side flanges, these retaining members
25 overlapping the adjacent edges of the linoleum pad, as at 20.

Referring to Fig. 6, instead of forming the tortuous rib along the underside of the board by folding a portion of the metal
30 sheet upon itself, this rib may consist of a separate tortuous strip of sheet metal, which is folded upon itself to form the vertical reenforcing and stiffening rib 21, and with horizontal flanges 22 disposed against
35 and welded, or riveted, or otherwise secured to the underside of a sheet metal plate 23, which forms the body of the running board.

It will be obvious from the above that the tortuous rib, in either modification, will
40 give the reenforcing and strengthening effect of two straight longitudinal ribs, and yet requires only the amount of metal necessary for one rib. It will be noted that, in addition to this medial reenforcement, the
45 sheet metal running board is reenforced along all of its edges, and that, when the top of the board is recessed, as shown in Figs. 4 and 5, the recessed portion acts as a stiffener for the edges of the board.

50 The rib in modification shown in Figure 2 may be formed in the following manner:—The groove is formed open by means of a punch in the first operation and is of the same tortuous shape as shown in Figure 1, the metal designated as 2 in Figure 2 being held flat during this operation between a pressure plate and a die. Then the board is positioned between an upper

pressure plate and slide members, and the slide members are moved inwardly to squeeze the rib walls together. The bending of the flanges around the edge of the board may be accomplished in a conventional manner.

As many changes could be made in the above construction and as many apparently widely different embodiments of this invention could be made without departing from the scope thereof, it is intended that all matter contained in the above description or shown in the accompanying drawings shall be interpreted as illustrative and not in a limiting sense.

What I claim is:—

1. As an article of manufacture, a running board for vehicle bodies comprising a plate having a tortuous rib extending longitudinally along the under side thereof, said rib comprising sheet metal folded upon itself. 75
80

2. As an article of manufacture, a running board for vehicle bodies comprising an integral piece of sheet metal folded upon itself along a tortuous line and forming a tortuous rib extending longitudinally along the underside of the board and substantially at right angles to the plane of the board. 85

3. As an article of manufacture, a running board for vehicle bodies comprising an integral piece of sheet metal folded upon itself along a tortuous line and forming a tortuous rib extending longitudinally along the underside of the board and substantially at right angles to the plane of the board, the outer edge of said piece being flanged downwardly and forming a reenforcing flange along the outer edge of the board. 90
95

4. As an article of manufacture, a running board for vehicle bodies comprising a plate having a tortuous rib extending longitudinally along the underside thereof, said plate having a recess along its top surface. 100

5. As an article of manufacture, a running board for vehicle bodies comprising a piece of sheet metal, having a tortuous reenforcing and stiffening rib extending longitudinally and medially along its underside, and having a reenforcing and stiffening depressed portion on its upper side, and having a downwardly extending reenforcing and stiffening flange along its outer edge. 105
110

This specification signed this 17th day of October, 1924.

ALBERT L. LAMBERT.
